UNITED STATES PATENT OFFICE.

EDWARD H. ANSHELM, OF NEW YORK, N. Y.

CORN RAZOR.

Application filed December 13, 1922. Serial No. 606,865.

To all whom it may concern:

Be it known that I, EDWARD H. ANSHELM, a citizen of the United States, residing at New York city, county and State of New 5 York, have invented a certain new and useful Corn Razor, of which the following is a specification.

This invention is a corn razor adapted more especially for use in the paring of 10 corns, callouses and the like and the object of the invention is to produce such an implement of integral one-piece construction, which may be employed without fear of 15 injury and which may be economically manufactured.

A further object of the invention is to 20 so construct a corn razor that it ordinarily requires no manual adjustment but will automatically adjust itself to effect the paring operation in a most efficient manner.

Corn razors as heretofore constructed invariably embody several parts adapted to 25 be assembled and adjusted by the user and in practically every instance the cutting blades are rigidly clamped in position 30 through the employment of various clamping means. The present invention in contradistinction is formed entirely from a single blank of material stamped out into 35 the desired configuration and thereafter bent into proper adjustment. The adjustment referred to is mechanically determined by the tools employed in the manufacture of the implement and the ultimate purchaser and 40 user is not required to assemble any parts or to vary its adjustment. The device is unusually simple in construction, yet highly efficient in the carrying out of its intended functions.

45 In its preferred practical form, it is constructed from a blank of sheet metal stamped up by suitable dies and of elongated shape. One end of the blank is sharpened to form a cutting edge and the blank is slotted transversely intermediate its ends to form a clearance slot. After the blanking operation is concluded and the cutting edge sharpened, the blank is manipulated by forming dies to 50 bend substantially one longitudinal half of the blank into curved configuration, leaving the other portion of the blank substantially straight whereby it is adapted to serve as a handle. The free end of the curved portion is returned upon itself so that the cutting 55 edge is substantially juxtaposed with the

clearance slot from which it is spaced a short distance.

In practice, the metal used is preferably more or less resilient so that the returned portion of the blank which carries the cutting edge, while adapted to normally maintain its fixed position, is capable of yielding slightly in the event that the cutting edge encounters a hard corn and as a result of this yielding action, the application of 60 excessive force which would be apt to result in cutting of the foot when the corn was finally cut through, is obviated and the device is rendered thoroughly safe in inexperienced hands. 70

Features of the invention, other than those specified, will be apparent from the following description and claims when read in conjunction with the accompanying drawings.

The accompanying drawings illustrate one 75 practical embodiment of the invention, but the construction therein shown is to be understood as illustrative, only, and not as defining the limits of the invention.

Figure 1 is a perspective view showing a 80 corn razor embodying this invention.

Figure 2 is an edge view of the razor shown in Figure 1.

Figure 3 is a rear elevation of the razor.

Figure 4 is a front view of the razor. 85

Figure 5 is a section on the line 5—5 of Figure 3; and,

Figure 6 is a view of the blank from which the razor is formed.

In constructing a razor shown in Figure 1 of the drawings, a blank such as shown in Figure 6 is first stamped from sheet metal. This blank may be divided for the purpose of graphic illustration into three parts which are designated in Figure 6 as 90 1, 2 and 3. The part 1 is to constitute the handle portion, the part 2 the guard portion and the part 3 the blade portion. These portions may be of any suitable contour, particular shapes being immaterial so far as the present invention is concerned. 95

The blank 1 is stamped out flat and during the blanking operation, the guard portion 2 is transversely slotted as shown at 4 to form a guide slot which as shown in Figure 6 is preferably of substantially the same length as the width of the blade portion 3, this blade portion 3 preferably being somewhat narrower than the guard portion 2. 105

After the blanking operation is completed, 110

the free end of the blade portion 3 is sharpened in any suitable manner to provide a cutting edge 5 and at the conclusion of this operation, the blank is ready to be formed into finished shape. This is accomplished by means of suitable forming dies and in practice is effected in two operations. That is to say, the handle portion 1 of the blank is left flat and constitutes the handle 1 of the implement, while the guard portion 2 is bent into substantially a half circle to form the semi circular guard 2 of the implement. The blade portion 3 is then bent back or returned over the exterior of the guard portion 2 to bring the cutting edge 5 in juxtaposition with the clearance slot, but nearer the further edge of said slot, so that between said further edge and the cutting edge, a relatively narrow space is left, as clearly appears from Figure 5. In bending back the blade portion 3, the curve of the bend is preferably swung on a relatively large arc, so as to not unduly crimp or fracture the metal and to furthermore provide a more or less resilient looped connection between the guard and the blade. The greater portion of the blade may if desired contact with the exterior face of the curved guard and, in practice, I find that this is preferable since such contacting relation between the parts maintains the cutting edge in very good adjustment relative to the juxtaposed edge of the clearance slot. The structure however is such that if the cutting edge strikes an unyielding corn, callous or other obstacle, the blade is adapted to give or yield slightly if excess pressure is applied through the handle. When the operator feels the blade give or yield, he will unconsciously relax the pressure and in so doing will be guarded against inadvertently forcing the blade through the obstacle with consequent quick acceleration of the blade after passage therethrough which is very apt to result in the cutting of the flesh. This constitutes one of the foremost dangers from corn razors when in inexperienced hands and marks the cause of the greater portion of injury resulting through their use.

The present construction entirely obviates the said danger of injury through the yielding connection referred to.

The finished implement is shown best in Figures 1-3, from which it will be apparent that the guard portion, as well as the blade, present to the skin a smooth curvilinear surface while the cutting edge of the blade is substantially tangential to this surface. This construction enables the razor to be readily guided during its operations and to slide easily over the skin. Moreover, the said convexity enables the cutting edge to be presented at the inclination or angle with reference to said curved surfaces which is

best adapted to secure the desired results in the use of the razor. The opposite ends of the cutting edge are rounded off as shown at 6, so as to eliminate sharp corners which would be apt to scratch or wound. In practice, I prefer to so proportion the width of the blade relative to the slot that the rounded portions referred to may rest upon the guide beyond the opposite ends of the slot and thus accurately space the cutting edge from the contiguous edge of the slot for the purpose of obtaining more accurate adjustment. This engagement is however not mandatory but can be dispensed with without departing from this invention.

It will be apparent from the foregoing detailed description that the implement of this invention is of unitary or one-piece construction and that the looping back of the blade from the forward edge of the guard is not only a highly practical method of construction, but produces marked efficiency of the razor when in use. Resilient properties of the connection referred to are idle when not employing the blade to pare corns and callouses as there is a vibratory action present which, though slight, gives very good results and is unknown in corn razors as now constructed. The drawings show the invention in its preferred form, but I wish it understood that slight changes in shape may be made without departing from the invention which is commensurate with the appended claims.

Having thus fully described the invention, what I claim as new and desire to secure by Letters Patent is:

1. A one-piece corn razor embodying a sheet metal blank, a portion intermediate the ends of which is longitudinally bent to form a guard which is provided with a transverse slot, one end portion of the blank serving as a handle and the other end portion of the blank being looped back over the outside of the curved guard and having a cutting edge juxtaposed with the slot and normally spaced from the edges of said slot by facial engagement of the blade with the guard.

2. A one-piece sheet metal corn razor embodying a substantially U-shaped guard provided at its base with a transverse slot, an integral upstanding extension on one arm of the guard constituting a handle and an integral blade turned back from the upper end of the other arm of the guard and longitudinally bent around the outer surface of the guard and terminating in a sharp cutting edge juxtaposed with the slot and maintained in proper adjustment relative to said slot by facial engagement between the blade and guard.

In testimony whereof I have signed the foregoing specification.

EDWARD H. ANSHELM.
